(57) **CLAIM**

The ornamental design for a container body portion, as shown and described.

DESCRIPTION

FIG. 1 is a top, front and right side perspective view of a container body portion showing our new design;

FIG. 2 is a front elevational view thereof;

FIG. 3 is a rear elevational view thereof;

FIG. 4 is a right side view thereof;

FIG. 5 is a left side view thereof;

FIG. 6 is a top plan view thereof; and,

FIG. 7 is a bottom plan view thereof.

The dashed line showing in the drawings is for illustrative purposes only and forms no part of the claimed design. The dot-dash-dot line showing in the drawings defines the boundary of the claim and forms no part of the claimed design.

1 Claim, 6 Drawing Sheets
